RESTAURANT FACADE OR THE LIKE

Fred Schmid, Los Angeles, Calif., assignor to Chicken Delight, Inc., Des Plaines, Ill., a corporation of Illinois

Filed May 10, 1968, Ser. No. 11,887

Term of patent 14 years

Int. Cl. D25—02

U.S. Cl. D13—1

I claim:

The ornamental design for a restaurant facade or the like, substantially as shown and described.
